ABSTRACT

Destination display webs mounted on various portions of a vehicle are operated in the same manner by providing a plurality of position detection elements for respective display sections of the display webs, a plurality of proximity switches — associated with respective webs to detect position detection elements and a control circuit responsive to the output from the proximity switches to stepwise move the display webs.

FIG. 2

PATENTED MAY 2 1972

3,660,835

SHEET 2 OF 2

FIG. 3

DESTINATION DISPLAY APPARATUS**BACKGROUND OF THE INVENTION**

This invention relates to destination display apparatus for use in a motor-bus and the like vehicle and more particularly to a destination display apparatus wherein a plurality of take-up motors of a plurality of display webs having the same displays are operated stepwise so that by selecting a display section of one display web other display webs are operated to display identical displays.

Electric cars and motor-busses operating in city areas are provided with destination display apparatus on their front, rear and side surfaces for the convenience of the passengers. In a prior art destination display apparatus a long web inscribed with a number of destinations and the like is wrapped about a take-up shaft in the form of a roll, and the shaft is operated manually to display the desired destination. For this reason where a number of such display apparatus are installed on front, rear and side surfaces of the vehicle it takes many hour and trouble to change the displays of all display apparatus in the same manner. This is especially troublesome for drivers of one-man cars.

SUMMARY OF THE INVENTION

It is therefore an object of this invention to provide a novel destination display apparatus which can vary in the same manner the destinations exhibited on a plurality of destination display apparatus.

According to a preferred embodiment of this invention there is provided a destination display apparatus comprising a plurality of display webs, each one of said display webs including a plurality of display sections for different destinations, an electric motor connected to one end of said one display web and a plurality of position detection elements associated with respective display sections; a plurality of proximity switches respectively associated with the display webs to detect the position detection elements thereof as the display webs are moved by the forward or reverse operations of the motors; and a control circuit connected to the outputs of the proximity switches to stepwise move the display webs in response to the outputs from the proximity switches and to stop the motors when the display webs are moved to display the next display sections.

Forward and reverse push buttons are mounted in the drivers cabin so that the driver can operate all display webs mounted on various portions of the vehicle in the same manner by merely operating the buttons while watching a display web mounted on the front side of the vehicle.

BRIEF DESCRIPTION OF THE DRAWINGS

In the accompanying drawings:

FIG. 1 is a perspective view of a destination display web embodying this invention;

FIG. 2 is a plan view of a portion of the destination display web showing the manner of mounting position detection elements;

FIG. 3 is a connection diagram of proximity switches and a logic circuit and

FIG. 4 shows a sequence control circuit for the destination display apparatus embodying this invention.

DESCRIPTION OF THE PREFERRED EMBODIMENT

Referring now to FIG. 1 of the accompanying drawings there is shown a destination display web 1 of a fabric and the like inscribed with a number of destinations and the like informations to the passengers. The web 1 is moved between a pair of take-up shafts 2 and 3. Shaft 3 is coupled to the driving shaft of an electric motor 4 while shaft 2 is driven by a rewinding spring 2' for rewinding the web. A plurality of position detection elements T₁, T₂ and T₃ are secured to the web 1 corresponding to respective destination display sections on the web. These elements may be made of magnetic material or

electro conductive material, and are positioned on a straight line opposite a proximity switch TL. As best shown in FIG. 2, position detection elements T₁, T₂ and T₃ are mounted at one end of respective display sections A, B and C respectively displaying destinations of the vehicle. It is to be understood that a destination display apparatus as shown in FIG. 1 is mounted on each of the front, rear and side surfaces of the vehicle.

As shown in FIG. 3, proximity switches TL₁, TL₂ and TL₃ are mounted respectively on the front, rear and side surfaces of the vehicle to cooperate with respective destination display webs 1 for detecting position detection elements mounted on the front or rear surface of the display webs. Thus, each proximity switch produces one pulse whenever one position detection element of the associated display web passes past it. Output leads from these proximity switches TL₁, TL₂ and TL₃ are connected to input terminals of NOT circuits N₁ to N₃ of a logic circuit LO comprising NOT circuits N₁ to N₅, an OR circuit, an AND circuit, a flip-flop circuit FF, diodes D₁ to D₇ and NOT circuits including current amplifiers NP₁ to NP₄ which are connected as shown in FIG. 3. The outputs of the negation circuits including the current amplifiers NP₁ to NP₄ are connected to auxiliary relays X₁ to X₄ respectively.

FIG. 4 shows a sequence control circuit of the destination display apparatus of this invention comprising contacts X₁₋₁, X₁₋₂, X₂₋₁, X₂₋₂, X₃₋₁, X₃₋₂ and X₄₋₁ of auxiliary relays X₁ to X₄, a forward push button PB₁ and a reverse push button PB₂ for a motor, auxiliary relays X₅ and X₆ having contacts X₅₋₁ to X₅₋₅ and X₆₋₁ to X₆₋₄, respectively, diodes D₁ and D₂, a capacitor C and operating coils M_{1-S} to M_{3-S} of electromagnetic switches for motors M_{1-R} to M_{3-R}, which are connected as shown in FIG. 4.

In operation, it is assumed that the destination display sections of respective display webs are adjusted to assume correct positions. For example, it is assumed that respective position

detection elements T₁ on respective display sections A are facing proximity switches TL₁ to TL₃. In this case all displays on the front, rear and side surfaces are the same, in this example UENO. Under these circumstances, since each one of output signals from the proximity switches TL₁ to TL₃ is a binary "1" the output signals from the NOT circuits N₁ to N₃ are a binary "0." As a result, the OR circuit provides a "0" output so that NOT circuit N₄ provides an output signal "1" reversing the flip-flop FF to generate an output signal "1." This output signal is coupled to auxiliary relay X₄ via NOT circuit N₅ and the NOT circuit including the current amplifier NP₄ to energize relay X₄ thus opening contact X₄₋₁ thereof shown in the sequence control circuit of FIG. 4. On the other hand the output signal "1" supplied to the inputs of the NOT circuits including the current amplifiers NP₁ to NP₃ from flip-flop FF causes these amplifiers to respectively produce output signals "0," thus deenergizing the auxiliary relays X₁ to X₃. Conversely, relay contacts X₁₋₁, X₁₋₂, X₂₋₁, X₂₋₂, X₃₋₁ and X₃₋₂ are maintained closed.

Under these conditions depression of forward push button PB₁ energizes auxiliary relay X₅ to close its contacts X₅₋₁ through X₅₋₃ and X₅₋₅ to form circuits through electromagnetic switches M_{1-S} to M_{3-S}, relay contacts X₁₋₁ to X₃₋₁, relay contacts X₅₋₂ and X₅₋₁, diode D₁ and forward push button PB₁ across terminals T₁ and T₂. Further, as current flows from terminal T₁ to diode D₁ via relay contact X₅₋₅, electromagnetic switches M_{1-R} to M_{3-R}, relay contacts X₁₋₂ to X₃₋₂ and relay contacts X₅₋₃ and X₁₋₁, drive respective motors in the forward direction to begin moving respective display webs.

As the display webs begin to move, all output signals of proximity switches TL₁ to TL₃ become "0" and all output signals from the NOT circuits N₁ through N₃ become "1." As a consequence, all inputs to AND circuit A become "1" to apply an output signal "1" to the reset input of the flip-flop circuit FF, causing it to reverse from the abovementioned state. Thus, the flip flop circuit FF provides a "0" output signal to deenergize auxiliary relay X₄ to close its contact X₄₋₁. Since the outputs from the NOT circuits N₁ to N₃ are "1," signals "1" are supplied to the inputs of the NOT circuits including the amplifiers NP₁ to NP₃ causing them to provide "0"

output signals. Thus auxiliary relays X_1 to X_3 are still being deenergized. Accordingly, currents still flow through electromagnetic switches M_{1-S} - M_{3-S} and M_{1-R} - M_{3-R} to continue the forward operation of motors.

Even when the position detection elements T_2 in the display sections displaying SENDAI on respective display webs come to confront respective proximity switches TL_1 to TL_3 at different times, each display web is positively brought to stop at the section displaying SENDAI. If it is assumed that the proximity switch TL_1 first detects the position detection element T_2 , only the output signal from this proximity switch TL_1 is "1" and the output signals from the other proximity switches are "0." Consequently, the NOT circuit N_1 will provide an output signal "0" whereas the NOT circuits N_2 and N_3 will provide output signals "1." Accordingly, the OR circuit provides an output signal "1" whereas the NOT circuit N_4 provides an output signal "0" and thus the flip-flop circuit FF is not reversed. Since the output signal from the NOT circuit N_1 is "0" and since the output signal from the flip-flop circuit FF is also "0," a "0" signal is applied to the input of the NOT circuit including the current amplifier NP_1 to generate a "1" signal to energize auxiliary relay X_1 . This opens relay contacts X_{1-1} and X_{1-2} to deenergize electromagnetic switches M_{1-S} and M_{1-R} thus stopping motor M_1 (not shown). Similarly, other motors M_2 and M_3 , not shown, are sequentially stopped.

Since each one of the NOT circuits N_1 to N_3 provides an output signal "0" when all motors M_1 to M_3 are stopped, all inputs to the NOT circuit N_4 will be "0" and this NOT circuit provides an output signal "1" to reverse the flip-flop circuit from the state shown in the drawing. Thus, all circuit elements are brought back to the condition prior to the depression of the forward push button. In this manner, each time the forward push button is depressed, the display sections of each display web are advanced stepwise to display the desired destination.

Where it is desired to change the display from section C to section A or B, the reverse push button PB_2 is depressed. Then auxiliary relay X_6 is energized to close its contacts X_{6-1} - X_{6-4} whereby the direction of the current flowing through electromagnetic switches M_{1-R} - M_{3-R} is reversed to reverse the direction of rotation of respective motors. The logic circuit shown in FIG. 3 operates in the same manner as the above described forward running and stopping operations of the motors.

Thus, the invention provides a novel destination display apparatus according to which the operator who depresses the forward or reverse push button while watching a display web on the front side of a vehicle can display the same destinations on other display webs.

While the invention has been shown and described in terms of a preferred embodiment thereof it should be understood that the invention is by no means limited to the illustrated embodiment and that many changes and modifications will be obvious to one skilled in the art without departing from the true spirit and scope of the invention as defined in the appended claims.

What is claimed is:

1. Destination display apparatus for a vehicle, comprising a plurality of pairs of take-up shafts;
- a plurality of display webs each connected at both ends thereof to each pair of take-up shafts, each of said display webs having a plurality of destination display sections for different destinations;
- a plurality of electric motors each coupled to a take-up shaft of each pair of take-up shafts;
- a plurality of position detection elements secured to portions corresponding to the respective destination display sections on each of the display webs;
- a plurality of proximity switches mounted on the front, rear and side surfaces of a vehicle to detect said position detection elements;
- a first plurality of NOT circuits each connected to the out-

put of a corresponding one of the proximity switches; an OR circuit connected to the outputs of the first NOT circuits;

an AND circuit connected to the outputs of the first NOT circuits;

a first additional NOT circuit;

a flip-flop circuit connected to the output of the OR circuit via the first additional NOT circuit for producing an output signal when each proximity switch detects said position detection elements and connected to the output of the AND circuit for resetting said flip-flop circuit when each proximity switch fails to detect said position detection elements;

a second plurality of NOT circuits;

a first plurality of auxiliary relays connected to the output of each of the first NOT circuits via the second plurality of NOT circuits and connected to the output of said flip-flop circuit to deenergize said first auxiliary relays when each proximity switch detects said position detection elements;

a second additional NOT circuit;

a third additional NOT circuit connected in series with the second additional NOT circuit;

a first additional auxiliary relay connected to the output of said flip-flop circuit through the connected second and third additional NOT circuits to energize said first additional auxiliary relay when each proximity switch detects said position detection elements;

a forward push button;

a second additional auxiliary relay;

a pair of terminals for connection to an electrical power supply;

a first series circuit connected in series with the forward push button for stepwise advancing said destination display sections and the second additional auxiliary relay, said first series circuit being connected across the pair of terminals;

a reverse push button;

a third additional auxiliary relay, each of the auxiliary relays and additional auxiliary relays having contacts controlled by them;

a second series circuit connected in series with a reverse push button for backing said destination display sections and the third additional auxiliary relay, said second series circuit being connected across said pair of terminals;

a first plurality of electromagnetic switches;

a parallel circuit comprising a second contact of each of the second and third additional auxiliary relays;

a first motor driving circuit forming a series shunt circuit by connecting a first contact of each of said first auxiliary relays and the first plurality of electromagnetic switches, both ends of said first motor driving circuit being connected to one of said pair of terminals and a connecting point between a first contact of each of said first and second additional auxiliary relays through the parallel circuit of a second contact of each of the second and third additional auxiliary relays to stepwise advance said destination display sections until each proximity switch detects said position detection elements;

a second plurality of electromagnetic switches; and

a second motor driving circuit forming a series shunt circuit by connecting a second contact of each of said first auxiliary relays and the plurality of second electromagnetic switches, both ends of said second motor driving circuit being connected to one of said pair of terminals and said connecting point through one of the contacts of said second additional auxiliary relay in order to stepwise advance said destination display sections until each proximity switch detects said position detection elements.

2. Destination display apparatus as claimed in claim 1, further comprising a rewinding spring having one end affixed to one end of a take-up shaft of each pair of take-up shafts and another end affixed to the vehicle.
